UNITED STATES PATENT OFFICE.

JOHN HAYS HAMMOND, JR., OF GLOUCESTER, MASSACHUSETTS.

VISIBLE GUIDE FOR VESSELS.

1,357,976.

Specification of Letters Patent.

Patented Nov. 9, 1920.

Application filed March 24, 1913, Serial No. 756,273. Renewed October 15, 1917. Serial No. 196,736.

To all whom it may concern:

Be it known that I, JOHN HAYS HAMMOND, Jr., a citizen of the United States, and a resident of Gloucester, in the county 5 of Essex and State of Massachusetts, have invented certain new and useful Improvements in Visible Guides for Vessels, of which the following is a specification.

My invention relates to visible guides 10 which are used to guide vessels from a distance, and relates more particularly to guides on torpedoes, torpedo boats and other vessels controlled from a distance, either by wire or by radiant energy, said guides, 15 herein shown as guide lights, being intended to be invisible to the enemy but visible to the observers at the controlling station, either on shore or on another vessel, from which the movements of said torpedoes and 20 other vessels are controlled and directed. It will be apparent, however, that the invention is equally applicable to air craft and land vehicles controlled and driven in any suitable manner by means of wires or radiant 25 energy or other suitable means. The type of guide herein disclosed, being a light, is particularly intended for use at night.

In the accompanying drawings:

Figure 1 shows, partly in diagrammatic 30 form, a warship and the course of an attacking torpedo or other craft with my guide light.

Fig. 2 shows a torpedo or submarine vessel equipped with my guide light.

Fig. 3 shows an elevation, partly in section, of my guide light and mast and the operating mechanism.

Fig. 4 shows a horizontal section, on the line 4-4 of Fig. 3, of my guide light and 40 mast and window frame and other attachments.

Fig. 5 shows an outside view of the mast and the window frame surrounding the light.

In Fig. 1, S is an enemy's warship, T¹, T² and T³ are successive positions of an attacking torpedo or other craft, directed and controlled from the shore station O, and L¹, L² and L³ are successive positions of my guide 50 light, which is seen to be always directed toward the station O, whatever the course of

the torpedo, and always invisible to the enemy.

In Fig. 2, T is a torpedo or submarine boat with two masts M and M¹. A is an antenna for receiving radiant energy. On the main mast M is fixed a frame F, containing glass windows of various colors and surrounding the light L.

In Figs. 3, 4 and 5, M is a hollow mast, 60 G represents a casing adapted to contain any well-known mechanism controlled by a gyroscope, and which is connected in any suitable manner with the bevel gearing C. The vertical shaft D connects bevel gearing 65 C with bevel gearing E, and the latter is connected by means of the shaft H with the gear wheel or pinion I, which gears with a circular rack J on the underside of the circular framework or wheel K. Framework 70 K can rotate on ball bearings B B around the mast M, and it supports the guide light L, which is provided with a combined screen and reflector R, which allows its rays to be emitted in only one direction. A frame F, 75 fixed to the mast M, contains windows W, W¹, W², W³, W⁴, W⁵, W⁶ and W⁷, preferably of glass each having a distinctive color.

The gyroscope is set so that when it is in operation it will hold the light L in such a 80 position that its rays are directed toward the controlling station. When the torpedo changes its direction, the gyroscope will maintain its fixed azimuth, and the mast M and gearing C and E will turn with reference to the gyroscope. The gear wheel I will therefore turn the circular framework 85 K carrying the light L so that the latter continues to face toward the controlling station. The frame F turns with the mast, and so different colored windows will be brought in front of the light L, and in this way the observer at the controlling station can determine the direction in which the torpedo is traveling and can direct its movements accordingly.

Instead of a gyroscope, I may use some other instrument or apparatus which will maintain a fixed azimuth, such as a compass needle. If a compass needle be used, it can 90 be so arranged as to cause various contacts to be touched when the torpedo, or other ves-

sel, swings around, and thus control mechanisms which will turn the light relatively to the vessel in such a way that the light will continually face in the same direction. The 5 compass needle can be inclosed in an iron case or otherwise protected from neighboring magnetic fields, or may be compensated for local attraction. The windows W, W¹, W², W³, W⁴, W⁵, W⁶ and W⁷ may be made 10 of any other suitable transparent substance besides glass, such as mica, and need not all be colored, and some of the window openings need not be glazed.

Instead of a light L, I can use a receiver 15 of light, such as the selenium cells shown in my application for United States Letters Patent Serial No. 702,174, which will then continually face toward the source of light that affects them and so get the full benefit 20 of the radiant energy, except when they are purposely screened therefrom.

My guide light may be applied to air craft and to land vehicles as well as to marine vessels, and these craft, vehicles or 25 vessels may be controlled from the operating station by means of wires or by radiant energy and may be driven and steered in any suitable and convenient manner.

The mast, gearing, window frame and 30 other parts of my apparatus and mechanisms may be altered as found suitable in any given case, and in general, I do not confine myself to the particular apparatus and mechanisms here shown, but various 35 changes and modifications, within the knowledge of those skilled in the art, may be made in the particular apparatus shown and described herein, without departing from the spirit of my invention, provided the means 40 set forth in the following claims be employed.

Having thus described my invention, I claim:—

1. In a system of distance control of vessels, a vessel containing a gyroscope which 45 maintains a fixed azimuth, a source of light, transmission mechanism connecting said gyroscope with said source of light, and a plurality of windows about said source of light.

50 2. An automatic guide light, comprising a source of light, a screen which permits the rays from said light to be emitted in only one direction, a plurality of windows surrounding said source of light, a gyroscope which maintains a fixed azimuth, and means 55 for connecting said gyroscope with said source of light.

3. An automatic guide light for moving bodies, comprising a source of light, a movable body rotatable with reference to said source of light, a screen surrounding said source of light on all sides except one and which is fixed with reference to said source of light, a plurality of windows surrounding said source of light and revoluble with

reference thereto, said windows being adapted to contain indicating devices, a gyroscope which maintains a fixed azimuth, and means for connecting said gyroscope with said source of light.

4. The combination with a vessel, of a pilot light mounted on said vessel, means on said vessel for maintaining a fixed azimuth operatively connected with said light to control the direction of the rays emitted therefrom, and indicating devices fixed to the vessel and having independent movement relative to said source of light.

5. The combination with a vessel, of a pilot light mounted on the vessel, a screen for said light fixed relatively thereto and having a single port for the passage of the rays of light, means for causing said port to point in a fixed direction independently of movement of the vessel, and indicating devices fixed to the vessel and having movement relative to said port.

6. In a system of distance control of movable bodies, a body adapted to be controlled from a distance and provided with a direction-indicating light, means associated with said light to effect differentiation in the apparent color thereof dependent upon the direction of movement of said body, and means operatively connected with said light to maintain the latter pointed in a fixed direction.

7. In a system of distance control of movable bodies, a body adapted to be controlled from a distance and provided with a direction-indicating guide, and means associated with said guide to effect differentiation in the visible effect thereof, dependent upon the direction of movement of said body, and means operatively connected with said guide to maintain the latter pointed with a fixed direction.

8. The combination with a movable body, of position indicating means carried by said body and having a portion movable with respect to said body, in a predetermined path, stabilizing means arranged to control said first mentioned means, and means to effect a variation in the visibility of said first mentioned means as a result of the rotation of said body in a given direction.

9. The combination with a movable body, of position indicating means carried by said body and having a portion movable with respect to said body, stabilizing means arranged to control the relative position of said position indicating means with respect to said body, and means to vary the apparent visibility of said position indicating means as a result of a rotation of said body about a given axis.

10. The combination with a movable body, of means for projecting a beam of light from said body, of means automatically operative to stabilize said beam, and means for

varying the visibility of said beam as a result of a rotation of said body with respect to said beam.

11. The combination with a movable body, of means for projecting a beam of light from said body, of means automatically operative to stabilize said beam, and means for varying the apparent color of said

beam as a result of a rotation of said body with respect to said beam. 10

This specification signed and witnessed this 18th day of March, A. D. 1913.
